US00D773305S

(12) **United States Design Patent** (10) **Patent No.:** **US D773,305 S**
Toh et al. (45) **Date of Patent:** **** Dec. 6, 2016**

(54) **CONTAINER**

(71) Applicant: **COLGATE-PALMOLIVE COMPANY**, New York, NY (US)
(72) Inventors: **Kiat-Cheong Toh**, Forest Hills, NY (US); **Thomas VanDyk**, Ramsey, NJ (US); **Roland Charriez**, Plattekill, NY (US); **David Demar**, Tenafly, NY (US); **Keith Kristiansen**, Stratford, CT (US); **Simon Dutton**, New City, NY (US)

(73) Assignee: **Colgate-Palmolive Company**, New York, NY (US)

(**) Term: **14 Years**

(21) Appl. No.: **29/502,646**

(22) Filed: **Sep. 18, 2014**

(51) **LOC (10) Cl.** **09-01**

(52) **U.S. Cl.**

USPC **D9/529**; D9/565; D9/449

Primary Examiner — Catherine Tuttle

(57) **CLAIM**

The ornamental design for a container, as shown and described.

DESCRIPTION

FIG. 1 is a perspective view of a container embodying our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are included for the purpose of illustrating environmental structure and form no part of the claimed design.

1 Claim, 5 Drawing Sheets
